UNITED STATES PATENT OFFICE.

SAMUEL M. LONGLEY, OF HUDSON, NEW YORK.

IMPROVED JOINTS FOR RAILROAD-BARS.

Specification forming part of Letters Patent No. 58,849, dated October 16, 1866.

To all whom it may concern:

Be it known that I, SAMUEL M. LONGLEY, of Hudson, in the county of Columbia and State of New York, have invented a certain new and useful Improvement in Joints for Railroad-Bars, of which the following is a full, clear, and exact description, reference being had to the accompanying drawings, forming part of this specification, and in which—

Figure 1 represents a plan of two contiguous lengths of rail in part, with their chair, intermediate connecting-piece, and fastening-keys; Fig. 2, a vertical section in direction of the length of the rails and through the latter; Fig. 3, a transverse section through the line *x x* in Fig. 1; Fig. 4, an end view of the chair; and Fig. 5, a view in perspective of the connecting-rail section detached.

Like letters refer to like parts in all the figures.

The nature of my invention consists in the interposition in the chair, between the ends of the rails, of a short rail section or connection of peculiar construction, and the chair which receives it and the ends of the rails of corresponding construction, whereby, while the usual amount of space at the joint is left for contraction and expansion of the rails, said space is divided or distributed, so as to reduce the gap or break at any one point, with every facility for removing the connecting-section when it is required to take out and replace or substitute a rail, and whereby the keys which hold the rails serve likewise to secure the connecting-section and are more effectually restrained from working loose in the longitudinal movement of the rails, also the latter, that may be in lap-gear with the connecting-section, protected against being battered at their ends and the junction of the rails with the chair, and, through the intervening section, with each other, generally improved.

For the information of others whom it may concern I proceed to describe my invention with reference to the accompanying drawings.

The rails or rail-lengths *A A* may be of the usual *T* form. *B* is one of the chairs into which the ends of the rails *A A* fit, but only project so far therein as to admit in between

them, with room for expansion, the body *a* of a short rail section or connection, *C*, which, when in its place, forms a continuation of the rail-surface.

The recess in the chair is enlarged where the body *a* fits, so that the latter is not only bound at its sides, but ends also, by the chair, and so that the rail-connection *C* may be inserted and removed vertically. Said body *a* has keyways *b b* through it on either side, tapering in opposite directions to each other, to admit of the keys *c c*, which serve to tighten up the rails in the chair on opposite sides, also tightening up or holding the rail-connection *C*.

The keys *c c*, on being driven home, thus bear not only against the sides of the rails and chair, but also against the latter and body of the rail-connection *C*. The ends of the rails may be cut away, as at *d d*, to receive the overlapping ends of said rail-connection.

From this description it will be seen that on taking out the keys *c c* and removing the rail-section *C* every facility is afforded for taking out the rails when it is necessary to repair or replace them by others; but the main use of the rail-section *C* is that by being arranged between the ends of contiguous rails it serves, by dividing the gap or break, to reduce by one-half the space at a single point necessary to be left for the contraction and expansion of the rails, as compared with arrangements having no such interposing piece, but giving the same room for contraction and expansion as the latter. In thus reducing the gap at a single point there is less injury to the rails and rolling-stock, and traveling over a line so constructed is made smoother or freer from jolts.

Furthermore, by the rail section or connection *C* being bound in the chair, as described, and the same keys which tighten the rails in the chair being wedged up between said rail-connection and the chair, longitudinal movement of the rails, by whatever cause it is produced, will not loosen the keys from their places, while by such mode of fastening, in conjunction with the lap of the rail-section on the rails, the ends of the latter are more fully protected from being battered or injured by

the action of the rolling-stock, and strain divided or communicated from one length of rail to the next.

What I claim as my invention, and desire to secure by Letters Patent, is—

The rail section or connection C, having keyways *b b*, and overlapping the rails at their top, in combination with the chair B and

rails A A, reduced at their ends, the whole being united by keys *c c*, and constructed and arranged to establish the joint, substantially as shown and described.

S. M. LONGLEY.
